United States Patent Office

Des. 196,433
Patented Oct. 1, 1963

196,433

DENTAL UNIT

Theodore M. Daalhuyzen, 2539 Adams Ave., and Leo Solomon, 8016 Plainfield Road, both of Cincinnati, Ohio

Filed Aug. 27, 1962, Ser. No. 71,460

Term of patent 7 years

(Cl. D24—1)

Fig. 1

The broken line showing of the dental chair and related equipment is included for illustrative purposes only.

We claim:

The ornamental design for a dental unit, as shown and described.
